CLAIM

The ornamental design for a walking cane, as shown and described.

DESCRIPTION

FIG. 1 is a side perspective view of a walking cane; and
 FIG. 2 is a front plan view thereof; and
 FIG. 3 is rear plan view thereof; and
 FIG. 4 is a left side view thereof; and,
 FIG. 5 is a right side view thereof.

The broken lines depict portions of the article that form no part of the claimed design.
